United States Patent

Des. 237,977
Patented Dec. 9, 1975

237,977

HOUSING FOR ELECTRONIC CONSOLE

Robert Brian Isaacs, Ottawa, Ontario, Canada, assignor
to Northern Electric Company Limited, Montreal,
Quebec, Canada

Filed Jan. 28, 1975, Ser. No. 544,853

Term of patent 14 years

Int. Cl. D13—03; D14—02
U.S. Cl. D26—5 R

FIG. 1

FIG. 2

FIG. 3

FIG. 4

FIG. 1 is a side elevational view of a housing for electronic console showing my new design;

FIG. 2 is a front elevational view thereof;

FIG. 3 is a top plan view thereof; and

FIG. 4 is a rear elevational view thereof.

The side of the device which is not shown is substantially identical to the side shown in FIG. 1.

I claim:

The ornamental design for a housing for electronic console, substantially as shown and described.
